Primary Examiner — Robin V Webster*Assistant Examiner* — Rachel A Voorhies(74) *Attorney, Agent, or Firm* — Oliff PLC(57) **CLAIM**

The ornamental design for a bicycle rack for vehicle, as shown and described.

DESCRIPTION

FIG. 1 is a front view of a bicycle rack for vehicle;

FIG. 2 is a rear view thereof;

FIG. 3 is a left-side view thereof;

FIG. 4 is a right-side view thereof;

FIG. 5 is a top view thereof;

FIG. 6 is a bottom view thereof;

FIG. 7 is a sectional view thereof taken along 7-7 in FIG. 1;

FIG. 8 is a sectional view thereof taken along 8-8 in FIG. 1;

FIG. 9 is a reference right-side view thereof showing the rack in an open state; and,

FIG. 10 is a reference right-side view thereof showing the rack in a state of use.

The broken lines depict environmental subject matter only and form no part of the claimed design.

1 Claim, 7 Drawing Sheets
